Primary Examiner — Cynthia Ramirez*Assistant Examiner* — Gino Colan(57) **CLAIM**

The ornamental design for a ladder bracket assembly, as shown and described.

DESCRIPTION

FIG. 1 is an isometric view of the ladder bracket assembly showing my new design;

FIG. 2 is another isometric view thereof;

FIG. 3 is a front elevational view thereof;

FIG. 4 is a right elevational view thereof;

FIG. 5 is a rear elevational view thereof;

FIG. 6 is a left elevational view thereof;

FIG. 7 is a top plan view thereof; and,

FIG. 8 is a bottom plan view thereof.
